UNITED STATES PATENT OFFICE.

CARL APPEL, OF SOUTH PASADENA, CALIFORNIA.

RAIL-BRACE.

1,300,101.

Specification of Letters Patent. Patented Apr. 8, 1919.

Application filed October 5, 1917. Serial No. 194,908.

To all whom it may concern:

Be it known that I, CARL APPEL, a citizen of the United States, residing at South Pasadena, in the county of Los Angeles and State of California, have invented certain new and useful Improvements in Rail-Braces; and I do hereby declare the following to be a full, clear, and exact description of the invention, such as will enable others skilled in the art to which it appertains to make and use the same.

This invention relates to improvements in rail braces.

The object of this invention is to provide a brace which is so constructed as to prevent the rails from spreading and getting out of gage, thus avoiding accidents caused by the rails spreading.

A further object of this invention is to provide a rail brace so constructed as to be locked with the ties so as to prevent them from slipping or spreading and acting to hold the rails in gage and avoid accidents caused by the spreading of the rails.

A still further object of this invention is to provide a rail brace of this character, which will be simple, practical and comparatively inexpensive in construction and one that can be manufactured and sold at a low cost.

With these and other objects in view, the invention consists in the novel combination and arrangement of parts hereinafter more fully described and set forth in the claims hereto appended.

In the drawings:

Figure 1 is a top plan view illustrating the application of my improved rail brace to the ties and rails.

Fig. 2 is a side elevation of the device applied.

Fig. 3 is a transverse sectional view of the same.

Fig. 4 is a bottom plan view of the plate.

Fig. 5 is a perspective view of the rail plate ready for use.

Fig. 6 is a perspective view of the spike used in connection with my rail brace.

Fig. 7 is a perspective view of the locking wedge shaped member.

Fig. 8 is a fragmentary sectional view illustrating the manner in which the wedge shaped member engages a tie for holding the same locked in the tie.

Like numerals of reference designate cor-

responding parts in all the figures of the drawings.

Referring to the drawings, the numeral 5 designates a railroad tie of the usual configuration having secured to the upper side 60 thereof the usual rails 6.

The rail brace is designated in its entirety by the numeral 7 and it comprises a rectangular body 8 which body is provided on its upper surface intermediate its ends with a 65 longitudinally extending recess 9 which is adapted to be bridged by the rail when set upon the body and thus permit water to drain from the device when set upon the ties. One side of the body 8 is extended to 70 provide a substantially tapered V-shaped extension 10 which extension is provided with an inverted V-shaped slot 11 defining a securing tongue 12. The extension 10 is bent 75 upwardly and inclined inwardly in the direction of the web and ball of the rail and is adapted to be engaged with the web adjacent the ball of the rail when the rail is set upon the body of the plate.

The supporting tongue 12 is provided with 80 a spike receiving opening 13 which communicates with the inner end of a groove 14 formed in the under side of the tongue 12. The groove 14 opens out through the end of the tongue 12 for facilitating the insertion 85 of a locking member therein, which will be hereinafter more fully described. The other side portion of the plate 8 is provided with spike receiving openings 15, it being understood that these spike receiving openings 90 and the spike receiving opening 13, are rectangular so as to receive spikes of the type now in use.

The openings 15 communicate with the inner ends of grooves 16 formed on the under side of the plate and extending from the outer edge thereof. These grooves 16 are adapted to receive locking members similar to the locking member placed in the groove 14 to hold the spikes in the openings 13 and 15 respectively against accidental removal therefrom incident to railroad stock passing over the rails 6.

The type of spike used in connection with my rail brace and illustrated in Fig. 6, comprises a shank 17 provided with a head 18 at one end and having its opposite end pointed as at 19 to facilitate driving of the same into ties 5 and through the openings 13 and 15. The spike is provided adjacent its head 110

end with a transverse groove 20 which has its upper wall inclined upwardly and outwardly as at 21.

A locking member 22 comprising a shank 23 having one end inclined as at 24 so as to fit into the groove 20 and engage the inclined wall 21 of the spike 17 and thus hold the spike against removal from the tie in which it is embedded is provided. The opposite end of the shank 23 is provided with a right angularly related head 25 which has a vertical groove 26 at its outer face forming vertical shoulders 27.

In use, the plates 7 are arranged upon the ties in the manner illustrated in Fig. 1 and the rails 6 are seated upon the plates 7, the ball being in engagement with the upper edge of the inclined brace 10. The spikes are then driven through the openings 13 and 15 respectively, with the grooves 20 in alignment with the grooves 14 and 16, respectively, of the plate 8, so that by inserting the locking members 22 into the grooves 14 and 16 so as to bring the inner ends 24 thereof into engagement with the grooves 20 of the spikes, the spikes are locked in the ties and secured against removal or accidental displacement by vibration. It is then only necessary to drive a nail or other suitable fastening member down in the groove 26 into the tie for preventing the outward movement of the locking member 22.

What is claimed is:

1. In a rail brace, a base plate adapted to

receive and support a rail, an upwardly and inwardly extending member carried by said plate and adapted to engage a rail mounted on the plate adjacent the point of juncture between the ball and web of the rail, and a securing tongue projecting from said plate in the plane thereof and positioned centrally of said extension, said tongue and the plate being provided with openings which are disposed in triangular arrangement for receiving securing spikes. 45

2. In a rail brace, a base plate adapted to receive and support a rail, said plate being of substantially rectangular shape, a bracing member formed integrally with said plate at one edge thereof comprising upwardly and inwardly inclined and upwardly converging arms integrally connected at their upper ends to form a substantially V-shaped brace element having its lower edge integrally secured to the edge of the base plate, and a securing tongue formed from the material defined by the arms of said brace element, said tongue being disposed in the plane of the plate and adapted to receive a securing member for tightly securing it to a tie. 50

In testimony whereof I affix my signature in presence of two witnesses.

CARL APPEL.
